METHOD AND APPARATUS FOR FORMING FLAT-SIDED TUBING

Lowell M. Kurtz, Scotia, N. Y., assignor to General Electric Company, a corporation of New York

Application September 28, 1939, Serial No. 296,931

9 Claims. (Cl. 153—67)

My invention relates to methods and apparatus for forming flat-sided tubing or tubing with a rectangular cross-section, and particularly to a method and apparatus for forming such tubing from tubing of round cross-section.

In the design of fluid circulating apparatus, it is frequently desirable to provide conduits having flat sides. For example, in heat exchangers such as those sometimes employed in refrigerating machines, it is necessary to provide as much area of contact as possible between the conduits conveying fluids at different temperatures in order to effect the maximum transfer of heat. When one conduit is wound around another as is frequently done in practice, it is desirable that the wound conduit be flattened to provide increased contact area, and it is common practice to provide flat conduits or conduits of rectangular cross-section for this purpose. The cost of such conduit is relatively high and a saving in cost may be effected by suitable flattening of the conventional round conduit. However, considerable difficulty has been encountered because of the tendency of the round conduit to buckle and prevent the formation of a flat side area. Accordingly, it is an object of my invention to provide an improved method for forming flat-sided or rectangular conduit from round conduit.

Another object of my invention is to provide an improved apparatus for forming a flat-sided or rectangular conduit from conduit of round cross-section.

Another object of my invention is to provide an improved apparatus and method for forming a helix of tubing of substantially rectangular cross-section from round tubing so that the helix may surround another tube or conduit and provide a greatly increased area of contact.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawings in which Fig. 1 shows an apparatus for constructing flat-sided tubing in accordance with my invention; Fig. 2 is an enlarged sectional view on the line 2—2 of Fig. 1; Fig. 3 is an enlarged top plan view of a portion of the apparatus shown in Fig. 2; and Figs. 4, 5, 6, 7 and 8 are enlarged sectional views on lines 4—4, 5—5, 6—6, 7—7 and 8—8, respectively, of Fig. 2, the sec-

tions in Figs. 6, 7 and 8 being further enlarged.

Referring now to the drawing, in Fig. 1 I have shown a machine or apparatus arranged to form a helical conduit 10 from tubing stock or conduit of round cross-section in such a manner that the cross-section of the conduit 10 is rectangular. Essentially the machine illustrated is a lathe comprising a bed 11 on which is mounted a stationary headstock 12 and a movable carriage 13, the position of which with respect to the headstock may be adjusted by rotation of the hand wheel 14. The carriage may be driven by a threaded shaft 15 through a suitable clutch actuated by a handle 16. The helical conduit 10 is formed on an arbor 17 held in a chuck 18 which is rotatably mounted in the headstock 12. The arbor 17 is provided with a helical groove 19 of shallow rounded or dished cross-section. The rates of rotation of the chuck 18 and shaft 15 are selected so that a conduit may be wound on the arbor 17 in alignment with the groove 19. In order to hold the conduit in the desired position and to guide it into place on the arbor, I provide a tool rest 20 in which a suitable tool holder 21 may be securely clamped by a threaded bolt 22, and within the tool holder 21 I mount a tool 23 arranged to partially compress the tubing stock and guide it onto the arbor 17. The position of the tool 23 with respect to the arbor may be adjusted longitudinally and transversely of the carriage 13 by turning cranks 24 and 25 respectively.

The arrangement of the tool 23 and the manner in which it is supported with respect to the arbor is shown in Figs. 2 and 3. I have found that the buckling or wrinkling effect produced by flattening round tubing may be counteracted by initially deforming the tubing in a suitable manner. I, therefore, construct the tool 23 so that it not only acts as a guide to carry the tubing into the desired position with respect to the arbor 17, but is also provided with a portion constituting a flattening or compressing die for changing the shape of the tube before it is wound on the arbor. The tool 23 is provided with a reduced cylindrical portion 26 which is fitted in the tool holder 21 and may be securely held in place by a threaded bolt 27. Within the portion 26 is a guide passage 28 having a width equal to that of the round tubing indicated at 29 and the upper portion of which is curved to conform to the curvature of the round tubing, as clearly shown in Fig. 4. The portion of the tool 23 between the tool holder and the arbor is constructed to form a tube flattening die and is pro-

vided with a removable section 30 so that the round tubing may be inserted in the tool and then flattened in the die portion of the tool by tightening of a pair of bolts 31 which secure the portion 30 to the remainder of the tool 23. When the tubing has once been secured in place in the tool and the tool is in position over the first turn of the arbor 17, the end of a length of tubing protruding beyond the tool 23 may be secured to the chuck 18 by a clamp 32 so that upon rotation of the chuck and arbor, the tubing will be drawn through the tool 23 and wound on the arbor. It will be noted that the tool 23 is arranged to guide the tubing until it is adjacent the arbor and is provided with a cut-away portion 33 conforming to the curvature of the arbor. The flattened portion of the tubing within the tool 23 is indicated at 34 and it will be noted in Fig. 2 that the lower edge of this portion moves in a path tangentially of the arbor so that it intersects the arbor since the shortest distance between the path and the axis of the arbor is less than the radius of the arbor. The tool 23 holds the tubing rigidly in this position and as the arbor is rotated the tubing is drawn tightly thereon and is compressed in a direction substantially normal to the plane of the flattened portion 34. The tubing is fed on the arbor at such a rate that it is maintained at all times directly over the helical groove 19.

The width of the groove 19 is somewhat less than the desired width of the finished flat side of the conduit which is to be formed on the arbor. The groove 19 counteracts the tendency of the tubing to buckle as it is wrapped on the arbor and facilitates the formation of a flat surface on the tubing adjacent the arbor. It will be understood that the term "flat" as used in this application has particular reference to the flattening of the cross-section of the tubing since it is obvious that the surface formed within the helical section of the tubing is cylindrical and not in a single flat plane.

Successive steps in the formation of the straight-sided tubing from the round tubing stock are illustrated in Figs. 4 to 8 inclusive. Fig. 4 shows the cross-section of the stock within the passage 28 of the tool. Fig. 5 shows the cross-section of the tubing after it has been flattened to form the portion 34. Fig. 6 shows the tubing being compressed just as it leaves the tool 23 and engages the arbor 17, it being noted that the curvature of the cross-section of the tubing 34 has been somewhat flattened adjacent the arbor. Fig. 6 also shows clearly the cross-section of the groove 19. Fig. 7 shows the further widening and flattening of the cross-section of the tubing as it leaves the tool and is being wrapped tightly on the arbor, the corners or contacting portions of the tubing having moved outwardly toward the sides of the groove 19; and Fig. 8 shows the final cross-section of the helical conduit 10 with the edges of the tubing resting on the arbor outside the groove 19. It is to be noted that the change of shape of the cross-section of the tubing is effected within a fraction of a turn of the arbor after the tubing has left the tool 23. The flat side of the cross-section shown in Fig. 8 lies directly over the groove 19 and the opposite or top side has also been flattened due to the inherent effect of the winding operation. It will be readily understood that the dimensions of the groove 19 will vary according to the weight and dimensions of the round tube stock from which the square tube is to be made. The most desirable

shape and size of the groove for a given size of tubing may be determined readily by trial.

From the foregoing, it is apparent that I have provided a simple and effective method and apparatus for producing conduit of rectangular or flat-sided cross-section from round tubing stock, and that this improved method and apparatus may be employed in a wide range of applications.

While I have illustrated and described my invention in connection with a particular apparatus and article, other applications will readily be apparent to those skilled in the art. I do not, therefore, desire my invention to be limited to the particular method and construction illustrated and described and I intend in the accompanying claims to cover all embodiments within the spirit and scope of my invention.

What I claim as new and desire to secure by Letters Patent of the United States is:

1. The method of forming tubing of substantially rectangular cross-section from round tubing which comprises partially flattening a length of round tubing to provide tubing having a cross-section with two substantially flat sides and two round sides, and thereafter pressing one of said round sides inwardly toward the center of the tubing along lines moving progressively apart as the side of the tubing is flattened until the desired width of the finished tubing has been obtained.

2. The method of forming tubing having a cross-section with at least one flat side from tubing having a cross-section with a round side which comprises providing an arbor having a groove around the periphery thereof, said groove having a width less than the desired width of the flat side of the finished tubing, and winding a length of the tubing having a round side onto the arbor with the round side of the cross-section thereof centered over the groove in the arbor whereby the compression of the tubing against the arbor flattens the round side thereof.

3. The method of forming tubing of substantially rectangular cross-section from tubing of round cross-section which comprises compressing a length of tubing of round cross-section to provide tubing of elongated cross-section, providing an arbor with a shallow groove of rounded cross-section around the periphery thereof, the groove having a width less than the desired width of a side of the finished tube, and winding the compressed length of tubing onto the arbor over the groove therein and with the longitudinal axis of the cross-section of the tubing substantially normal to the axis of the arbor, whereby the side of the tubing adjacent the arbor is flattened.

4. The method of forming tubing of substantially rectangular cross-section from tubing of round cross-section which comprises compressing a length of tubing of round cross-section to provide tubing of elongated cross-section; providing an arbor with a groove around the periphery thereof, the groove having a width less than the desired width of a side of the finished tubing; guiding the compressed length of tubing toward the arbor in alignment with the groove therein, with the longitudinal axis of the compressed section of said tubing substantially normal to the axis of the arbor, and with the shortest distance between the extended path of the tubing and the axis of the arbor less than the radius of the arbor; and winding the tubing onto the arbor whereby the side of the tubing adjacent the arbor is compressed and flattened over the groove in the arbor.

5. The method of forming from round tubing a helix of tubing the cross-section of which is flat toward the center of the helix whereby the helix is adapted to engage substantial areas of a cylindrical body arranged therein, which comprises compressing a length of round tubing to provide tubing of elongated cross-section, providing an arbor with a helical groove around the periphery thereof, the groove having a width less than the desired width of the inner side of the finished helical tubing, guiding the compressed tubing onto the arbor with the longitudinal axis of the cross-section thereof substantially normal to the axis of the arbor, and winding the tubing tightly onto the arbor over the groove therein whereby the side of the tubing adjacent the arbor is flattened and a helix of tubing is formed on the arbor.
6. The method of forming tubing of substantially rectangular cross-section from round tubing which comprises providing an arbor with a groove around the periphery thereof, the groove having a width less than the desired width of a side of the finished tube, and partially flattening the tubing and winding it onto the arbor over the groove therein with the axis of the flattened portion thereof substantially normal to the arbor whereby the side of the tubing adjacent the arbor is flattened.
7. Apparatus for forming flattened tubing from tubing of round cross-section including an arbor having a groove therein, the width of the groove being less than the desired width of a flat side of the finished tubing, means for rotating the arbor and for winding the tubing onto the arbor, and means for guiding the tubing onto the arbor in alignment with said groove.
8. Apparatus for forming flattened tubing from tubing of round cross-section including an arbor having a groove therein, the width of the groove being less than the desired width of a flat side of the finished tubing, means for rotating the arbor and for winding the tubing onto the arbor, and means for partially flattening the tubing and for guiding the tubing onto the arbor in alignment with said groove.
9. Apparatus for forming a helix of tubing of substantially square cross-section from round tubing which includes a rotatable arbor having a helical groove therein, the width of the groove being less than the desired width of the cross-section of the finished tubing, means for partially flattening the tubing and for guiding the tubing onto the arbor and for maintaining the longitudinal axis of the flattened cross-section thereof substantially normal to the axis of the arbor, means for moving said guiding means along the arbor dependent upon rotation of the arbor to maintain said guiding means in alignment with said groove.
